UNITED STATES PATENT OFFICE.

JOHN EDMUND PERRY, OF SHARON, PENNSYLVANIA, ASSIGNOR TO VALLEY MOULD & IRON CORPORATION, OF SHARPSVILLE, PENNSYLVANIA, A CORPORATION OF NEW YORK.

INGOT-MOLD CORE BOX.

Original application filed May 14, 1924, Serial No. 713,123. Divided and this application filed November 27, 1925. Serial No. 71,609.

The present invention relates broadly to metallurgy and more particularly to the art and apparatus for casting ingot molds.

In my copending application, which even-
5 tuated in Patent No. 1,620,128, patented March 8, 1927, I have disclosed a mold set up for casting ingot molds, in which set up the core is accurately and securely held in a central position with respect to the mold
10 flask by means of interfitting parts, thus eliminating errors of judgment in making the set up and also eliminating the possibility of accidental displacement of the core with respect to the mold flask. The present
15 application is a division of said prior application and the invention herein claimed is the core bar and box organization, the core bar, and the method of making the core disclosed in said parent application. The in-
20 vention claimed in this application is par-
ticularly useful in producing the core used in the set up of the parent application, but in its broader aspects, the invention may be utilized in other relationships.
25 The invention greatly simplifies the pro-
cedure of the prior art by providing a core bar having parts adapted to interfit with parts of the mold and by providing a core box with parts interfitting with the core bar,
30 thereby eliminating the element of chance or skill both in sand ramming the core bar and in setting up the core bar for casting. The present invention enables the various opera-
35 tions to be carried on with certainty and with much less skilled labor.

In carrying out the invention, the core bar is provided with a relatively large base which is fixedly and rigidly secured to the core bar standard. Preferably, this base is sufficient-
40 ly larger than the core bar to extend be-
neath the matrix in the mold set-up with which it is to be used and also to extend out under the bottom portion of the flask. The peripheral edge of the base is preferably
45 provided with an upstanding rim which is adapted to contact with a heavy stripping plate or bottom of the flask with which the core is used. Thus when the core is placed in a mold set up the flask may set partly on
50 the casting bottom and partly over the base of the core bar. The core bar base may set in an opening in the casting bottom that is exactly centered relative to the casting bottom.

When the core bar is ready for ramming a layer of sand is arranged over a dish-shaped portion of the core bar base. This base of the core bar exactly fits into a ramming base on the core bar box. The sides of the core bar box are cast iron doors or 60 sides which are hinged to the ramming base like a pair of gates and close over the base of the core bar to rest upon the up-standing edge of this base, thereby accurately posi-
65 tioning and locking the core bar vertically 65 in the ramming box to securely maintain the parts in this position during the ramming operation. The edges of the sides of the box smooth down the sand which was rammed in the dish-shaped portion of the core bar 70 base. Mold sand is now rammed around the sides of the core bar column, which may be when desired, of any well known col-
lapsible type or it may be non-collapsible. After the ramming operation is completed 75 the core bar box is opened and the core is lifted by a crane and set aside to dry, after first being blackened. It will be ob-
served that the large heavy base on the core 80 bar provides a complete support for the bottom portion of the sand packed around the core bar. After the core is dried, it is picked up by a crane and set into a suitable opening provided with machined sides in the casting bottom which correctly positions it 85 with respect to the other parts of the mold which may also be set on the bottom.

In this manner, the operations proceed in regular order without any removal of the parts after they have been set up, as was the old practice; furthermore, the parts are se-
curely locked together so that it is possible to utilize a set-up embodying the present core bar for casting on moving platforms or buggies or carriages which may be very de-
sirable, but which could not be performed by a set-up under the old practice.

Having generally described the invention, it may be stated that an object is to provide an improved core bar which may be inter-
locked with the parts of a suitable mold in such manner as to maintain accuracy of set-
up without sacrifice in economy of time or labor to secure the desired result.

Another object of the invention is to pro-
vide a core box hinged to a ramming base whereby said core bar may be seated in a predetermined position thereon and the sides

of said box may be readily swung about the core bar to complete the set-up for ramming.

A further object of the invention is to provide a core bar rigidly mounted upon a supporting base, which is of sufficient size to permit its outer periphery to extend beyond the sand mold on the core bar and to be engaged by the flask in a suitable mold set-up, whereby the core bar is held rigidly in a predetermined vertical position.

Other and further objects of the present invention will in part be obvious and will in part be pointed out hereinafter by reference to the accompanying drawings, throughout which like parts are designated by like characters.

It is recognized that the present invention may be embodied in constructions and practiced by steps other than those herewith specifically disclosed; therefore, it is desired that the disclosure herewith shall be considered as illustrative and not in the limiting sense.

Fig. 1 is a vertical cross sectional view of 25 a collapsible core bar before being rammed;

Fig. 2 is a plan view of the base of a core bar ramming box;

Fig. 3 is a cross section through the core bar in position in the ramming box;

Fig. 4 is a cross section of the ramming box taken adjacent the base thereof;

Fig. 5 is a cross section through a set-up ready for casting having the improved core bar therein, and

Fig. 6 is a detail view of a portion of the base of a core bar where the base comprises a chill flange for chilling the bottom of an ingot mold cast in the set-up.

Referring now more especially to the drawings, which illustrate a preferred embodiment of one form of device for carrying out the present invention, the core bar comprises a pedestal 2, which may carry the movable collapsible sides 4, as is common in

the art. The pedestal 2 is fixedly mounted upon a heavy base 5, which may be formed on its upper surface as a dish-shaped member having a depressed portion 6 and a rim portion 7. Projections 8 may extend upwardly from the bottom of the depressed portion in order to provide supporting members for sand which may be filled in over the dished portion. The base 5 is provided with short lugs or legs 9 on which the bar

55 may stand when not in use. The sides of the bottom of the core bar have machined ribs 10 thereon which are downwardly and inwardly inclined.

The base 11 of the core bar ramming box 60 is provided with a depression 12 which also has machined ribs 14 which have machined surfaces inclined exactly to correspond to the inclination of the surface on the machined ribs 10 on the base 5 of the core bar.

Preferably sand openings 15 are provided

in the bottom between the ribs 14 to permit any sand which works between the ramming base and the core base to filter through and get out of the way. The upper face of the ramming base is provided with curved machined tracks 16 that form supports for the bottom flanges 31 of the trough-like core box sections 17 and 18 which form the side walls of the core box. These sections are hinged together by long hinge arms 19 pivoted at 13 so that after the core bar base 5 is set in the depression 12 in base 11 of the core box, thereby accurately positioning the core bar in the box, these cast core box sections 17 and 18 may be swung closed to 70 surround the core box. The pivot 13 of the long arms 19 is located at a corner of the core box preferably on a diagonal of the core box matrix. The arrangement of the long arms 19 and the pivot 13 is such that 75 when the core box is opened or closed the sides have a transverse bodily movement somewhat like the blades of a shear. This is important when the core box is opened as it causes the sides to move bodily away 80 from the sand face on the core bar and obviates injury to this delicate sand face. Before the sections are closed however, sand is rammed over the dish-shaped portion of 85 the core bar base so as to form a rammed sand surface extending outwardly from the base of the pedestal of the core bar. After the sections of the core box are closed and locked together by C-clamps 32 or other locking means, the sand is rammed around 90 the core bar as illustrated in Fig. 3.

While the features of the above described core bar are applicable to mold set-ups generally, their advantages are more readily attained with a flask and supporting base, 105 such as shown in my copending application, which eventuated in Patent No. 1,620,128, issued March 8, 1927, referred to hereinbefore. A cross sectional view of the preferred set-up is shown in Fig. 5, wherein 110 the core bar after having mold sand applied thereto, blacked and dried, is set in a depression 21 in a casting bottom 22, which depression is likewise provided with machined supporting surfaces or ribs 24. These 115 surfaces contact with the similar surfaces 10 on the core bar base and accurately position the core bar relative to the casting bottom. A flask 25 is then set down over the core bar and on to the casting bottom. When 120 this happens a stripping plate 26 on the bottom of the flask extends over the rim 7 on the core bar base 5 and securely locks the core bar in position. If the face has not been accurately set, the weight of the flask 125 straightens it up. Before the flask is set over the base, the workmen may run dry sand in the space between the machine supporting surfaces 10 and 24 and the core bar base 5. Preferably C-clamps 27 are used 130

to clamp the flask and casting bottom together after the flask has been set over suitable dowel pins (not shown) carried by the casting bottom 22, so that the set-up 5 is very secure and rigid and is not disturbed by vibration which may be caused by moving cars or conveyors on which this mold set-up may be placed if desired. It will be noted that the base 5 of the core bar is sufficiently large to extend outwardly to support the sand mold on the core bar and in addition to extend under the sand mold on the flask 25 to permit its outer rim to be engaged by the flask or the stripping plate 10 thereon, whereby the flask serves as a positive means for holding the core bar in a predetermined position on the casting bottom.

This construction presents such accurate 20 and rigid fittings that there is little danger of any fins being formed on the bottom of the cast mold, but it will be observed that immediately back of the bottom edge of the matrix the seam or joint is formed between 25 the cold metal rim 7 on the core base 5 and the cold metal stripping plate 26 on the bottom of the flask, and consequently is a cold metal to metal joint. Therefore, if any of the hot iron should tend to leak into this 30 joint, it is immediately chilled as soon as it strikes a cold metal to metal contact and will not proceed beyond this point.

There may be conditions where it is desired to utilize a chill at the bottom of the 35 mold, and where this is desired, the base 5 of the core bar is not cut away to form a dish shaped member, but is left full and solid as is indicated at 29 in Fig. 6.

From the foregoing, it will be observed 40 that the parts are so constructed and inter-fitted as to automatically center and inter-lock the core bar in the core box, thereby obviating the necessity for hand setting and also obviating inaccuracies which are necessarily attendant with hand set-ups. By 45 means of the present construction standardized core bar bases and casting bases may be utilized with different sized ingot mold flasks so that a relatively few number of casting 50 bottoms may be used with several different sizes of flasks. This is of importance because the casting bottoms can be laid out on the casting floor or set upon cars or conveyors without requiring frequent changing.

55 The other parts comprising the flask and core bars are lifted to and from these bases during the set-up and stripping operations and the bases are changed only when widely different molds are to be cast, thereby economizing in time and crane movement.

Having thus described my invention, what I claim is:

1. A device of the class described comprising a core bar ramming box and a base 65 therefor adapted to seat a core bar, and

means for mounting the parts of said ramming box on said base, and guides on said ramming box and said ramming box base adapted to position same about a core bar.

2. As an article of manufacture, a core 70 bar ramming box and a base therefor, means for pivoting the parts of said ramming box to said base therefor to permit said parts to swing about said pivot to close and open said box about a core bar, and means 75 independent of said pivot to support said parts.

3. In a device of the class described, the combination of a core bar having a base 80 rigidly attached thereto, a core bar ramming box comprising a pair of trough like members hinged together at one side thereof, a ramming base for said box having a seat adapted to receive the base of said core bar, 85 means for pivotally connecting said members to said ramming base, and means on said base and said members for guiding said members over said core base and determining the position of said ramming box with respect to said core bar, said members engaging 90 said core bar base to hold said core bar in said position.

4. In a core bar adapted to be used in casting ingot molds, the combination of a 95 pedestal and a supporting base rigidly secured thereto, said base being adapted to receive a layer of mold sand about said pedestal, and having a rim extending around the outer periphery thereof to prevent metallic fins on the mold cast thereabout. 100

5. As an article of manufacture, a core 105 box comprising a base, side wall sections mounted over said base, long hinge members connecting said side wall sections to said base to cause a bodily outward movement to 110 said side wall sections when said core box is opened, and supporting means independent of said hinge to support the weight of the side wall sections.

6. As an article of manufacture, a core 110 box comprising a base, side wall sections mounted to slide upon said base, and a hinge adapted to guide the movement of said side wall sections, said hinge being located substantially upon a diagonal of the matrix of 115 said core box.

7. As an article of manufacture, a core 120 box comprising a base, side wall sections mounted upon said base, and tracks carried by said base to support said side wall sections during opening and closing movements.

8. As an article of manufacture, a core 125 box comprising a base, side wall sections slideable upon said base and with the weight of said side wall sections being supported by said base, and means to cause said side wall sections to move bodily away from a core within said core box when the box is opened.

9. As an article of manufacture, a core 130

bar ramming box comprising movable side walls having substantially vertical matrix faces, and means adjacent the bottom edges of said side walls provided with substantially horizontal matrix faces.

10. The combination of a core box ramming base adapted to receive a core bar base, a core bar having a vertically extending portion and a base adapted to fit within said core box ramming base, and core box side members having horizontal faces extending over said core bar base and vertical faces extending upwardly from said horizontal faces.

11. The combination of a core box ramming base adapted to receive a core bar base, a core bar having a vertically extending portion and a base adapted to fit within said core box ramming base, a rim around the edge of the core bar base, and core box

side members having horizontal faces extending over said core bar base and vertical faces extending upwardly from said horizontal faces, said horizontal faces being adapted to contact with the top of the rim 25 on the core bar base.

12. A core bar ramming box comprising a base member adapted to support a core bar, and heavy vertical sides mounted on said base member and adapted to extend over 30 sand on a portion of a core bar base.

13. A core bar ramming box comprising a base member having a recess with inclined faces thereon adapted to support a core bar, and heavy vertical sides mounted on said base and having a horizontal portion adapted to extend over a portion of said recess 35 to engage the core bar base and accurately center the core bar in the core box.

JOHN EDMUND PERRY.
